UNITED STATES PATENT OFFICE

163,121

BUTTER SPREADER FOR EARS OF CORN
AND THE LIKEHenry S. Kane, Chicago, Ill., assignor to Amper-
ized Tool Corp., Chicago, Ill., a corporation of
Illinois

Application May 10, 1950, Serial No. 9,845

Term of patent 3½ years

(Cl. D44—29)

To all whom it may concern:

Be it known that I, Henry S. Kane, a citizen of the United States, residing at Chicago, in the county of Cook and State of Illinois, have invented a new, original, and ornamental Design for a Butter Spreader for Ears of Corn and the like, of which the following is a specification, reference being had to the accompanying drawing, forming part thereof.

In the drawing:

Figure 1 is a plan view of a butter spreader for ears of corn and the like, showing my new design;

Figure 2 is a side elevational view of the same;

Figure 3 is a bottom view of the same;

Figure 4 is a side view taken in section on the line 4—4 of Figure 1; and

Figure 5 is an end view taken in section on the line 5—5 of Figure 1.

I claim:

The ornamental design for a butter spreader for ears of corn and the like, as shown.

HENRY S. KANE.
